UNITED STATES PATENT OFFICE.

JESSE C. MARTIN, JR., OF SAN FRANCISCO, CALIFORNIA.

INTERLOCKING BRICK.

Application filed March 29, 1922. Serial No. 547,729.

To all whom it may concern:

Be it known that I, JESSE C. MARTIN, Jr., a citizen of the United States, residing at San Francisco, in the county of San Francisco and State of California, have invented certain new and useful Improvements in Interlocking Brick, of which the following is a specification.

The invention relates to bricks, and has as an object the provision of a brick having elements on its surfaces adapted to interlock with complementary elements upon like bricks upon which it is superimposed or which are superimposed upon it.

15 A further object of the invention is the provision of an interlocking brick wherein the faces of the bricks about the interlocking elements will come into close contact with certainty and will not be held apart by contact of the interlocking elements.

An illustrative embodiment of the invention is shown in the accompanying drawings, in which—

Fig. 1 is a plan view;

25 Fig. 2 is a vertical longitudinal section on line 2—2 of Fig. 1 showing portions of superposed bricks in dotted lines.

The brick provided by the present invention may be of any desired size and shape, but preferably of the usual dimensions with length twice its width. A difficulty with interlocking bricks provided with bosses and receptacles heretofore used in laying a wall without a mortar joint, as in fire brick for furnace settings, has been that the bosses were likely to come into contact with the bottoms of the receptacles before the general faces of the bricks about the interlocking elements came into contact.

40 To obviate the named difficulty the bricks embodying the present invention are made with bosses 10 extending above the general face 11 of the brick and to interlock with the bosses of other like bricks the opposite face of the brick is provided with receptacles 12 extending into the body of the brick from the general face 13 of this side of the brick. The depth of the receptacles 12 is, as shown, greater than the height of the bosses 10.

50 During the firing, especially with bricks fired at a high temperature, the clay of which the brick is formed shrinks. The shrinkage of the different parts of a kiln is not equal. To make it possible to use a brick which was

fired in the portion of the kiln where greatest shrinkage takes place, with a brick fired in the portion of the kiln where less shrinkage takes place, indifferently in the wall, the difference between the height of the boss and the depth of the receptacle is made in excess of the maximum difference of shrinkage.

Moreover to ensure that the boss will not ride on the walls of the complementary receptacle when the bricks are laid the horizontal dimensions of the boss are also made less than the horizontal dimensions of the receptacle a sufficient amount to allow for the difference in shrinkage with certainty.

When used without a mortar joint, as is the practice in laying fire bricks in furnaces, the bricks are commonly dipped in a mud of fire clay to provide a thin coating on the surface, which coating on the successive bricks may adhere. It is important that the faces of the brick come into close contact not only so that there shall be no cracks but also that the joint between them which is the weakest portion of the wall and most susceptible to the action of the heat shall be as thin as possible. It is under these conditions that the value of the present invention is greatest.

To enable the bosses to enter the receptacles readily they are made as shown of tapering form, or in the form of the frustum of a cone, the receptacles having a corresponding form with the appearance above referred to. While the bosses and receptacles shown in the drawing for purposes of illustration are circular in plan, it will be understood that this showing is for purposes of illustration only, and that the form of the interlocking elements may be anything desired, so long as the depth of the receptacle is greater than the height of the boss with which it is to interlock.

As illustrated the bosses and also the receptacles are spaced equidistantly from the adjacent end of the brick from the side surfaces and from the center line 14 thereof.

Minor changes may be made in the physical embodiment of the invention without departing from its spirit.

I claim as my invention:

1. A brick having a boss upon one surface and a receptacle indented in its opposite surface, said boss and receptacle adapted to interlock with a receptacle and a boss upon

contiguous bricks in a wall, the height of the boss being less than the depth of receptacle whereby the surfaces of the bricks surrounding the interlocking boss and receptacle may be brought into close contact.

2. A brick comprising a body having a plurality of bosses upon a surface thereof, a plurality of receptacles upon the opposite surface thereof, said receptacles being opposite said bosses and adapted to interlock with complementary receptacles and bosses upon contiguous bricks in a wall, the depth

of the receptacles being greater than the height of the bosses.

3. A brick having bosses upon a surface thereof and receptacles indented upon the opposite surface thereof, the bosses and receptacles being coaxial and each being spaced equally from an end, the sides and the center line of the brick, the depth of the receptacles being greater than the height of the bosses.
